UNITED STATES PATENT OFFICE.

WILLIAM M. SIMPSON, OF CHICAGO, ILLINOIS.

BRAKE-SHOE.

1,027,081.

Specification of Letters Patent.

Patented May 21, 1912.

Application filed March 30, 1911. Serial No. 617,811.

To all whom it may concern:

Be it known that I, WILLIAM M. SIMPSON, a citizen of the United States, residing at Chicago, in the county of Cook and State of Illinois, have invented certain new and useful Improvements in Brake-Shoes, of which the following is a specification.

This invention relates to railway brake shoes of that class which have a cast metal body reinforced or strengthened by a plate of wrought iron, steel, or other suitably tough material located at or adjacent to the back of the body and an attaching lug made of tough ductile material anchored to the shoe body. In shoes of this type the wrought metal attaching lug has heretofore been anchored to the shoe body by tucking the ends of the lug under the sides of the reinforcing plate and embedding these tucked-under ends in the cast body of the shoe. In practice the strap lug is formed with the inwardly projecting ends and the plate is engaged with this lug by tilting the plate and passing it through the opening between the ends and into the eye of the lug. Owing to the limited dimensions of the eye of the strap lug it is necessary to make the opening between the ends of the lug as wide as possible to permit the insertion of the plate therein, as just described, and hence these ends overlap the plate when the latter is properly arranged in the eye just sufficiently to hold the plate in place during the operation of casting the body of the shoe thereon. It has been found by an examination of commercial shoes of this type that the plate or lug has shifted in the casting operation, or the ends of the lug have been separated more than usual, and one of the ends is disengaged from the plate and only one end of the strap lug is tucked under the plate. Owing to the high braking pressure now required by the present heavy equipment these, as well as other shoes, are often fractured in service, as well as in handling, and the cracks or fractures most frequently occur near the center of the body where the attaching lug is anchored. When the shoes with the attaching lug ends tucked under the reinforcing plate, in the manner customarily employed in commercial practice as hereinabove described, are thus fractured the lug and shoe will be easily separated under the strains of travel. This not only involves the loss of the shoe but it may permit the body

to fall in a frog or switch and be the cause of a wreck.

It is the object of my present invention to produce a shoe having a wrought metal attaching lug so securely anchored to the shoe body that it can not be detached therefrom even if the shoe body should become cracked or fractured. This result is accomplished by certain novel features of construction which will be best understood by reference to the following description when taken in connection with the accompanying drawings, throughout the various views of which like reference characters refer to similar parts.

On the drawings, Figure 1 is a plan view showing the reinforcing plate and lug embodying my invention, the body being indicated in broken lines. Fig. 2 is a longitudinal sectional view thereof. Fig. 3 is a transverse sectional view on the line 3—3 of Fig. 2. Fig. 4 is a transverse sectional view on the line 4—4 of Fig. 2; and Fig. 5 is a plan view of a modified form of a reinforcing plate.

Referring to the drawings, 6 is the body of the brake shoe and it is made of cast iron and of any approved shape. A reinforcing plate 7 is disposed at or adjacent to the back of the shoe body, said plate being of any well-known or desired contour having, if preferred, beveled edges 8, as shown in Fig. 1, and, if desired, notches 9 or other indentations or recesses to permit the entrance of the metal of the shoe body for the purpose of forming a locking engagement between the body and the plate. In this form the plate is also shown provided with longitudinally extending slots 10 and transverse slots 17 into which the metal of the shoe body is permitted to flow. The end lugs 11 and the guide lugs 12 are also formed by the body metal which flows up around the sides and ends of the plate.

The attaching lug 13 consists of a metal strip or strap stamped and bent to the desired shape illustrated in the drawings. The plate 7 is provided with a centrally disposed aperture 14 through which the central portion of the attaching lug is projected to engage the lug with the plate before the body of the shoe is cast thereon. The strap lug illustrated in full lines in Fig. 2 is entirely open at the sides of the shoe and the ends 15 of the lug are disposed beneath the plate and extend longitudinally thereof in opposite

directions. I prefer that the ends 15 of the lug should lie adjacent to and preferably parallel with the underface of the plate and they are provided with perforations 16 to align with the perforations 17 in the plate on either side of the aperture 14. The perforations 17 are preferably larger in size than the underlying projections 16 to permit the body metal to spread out in the 10 perforations 17 and form rivet heads which assist in securing the reinforcing plate and attaching lug to the shoe body. To further insure retention of the attaching lug in position and prevent it from being withdrawn 15 from the shoe through the aperture 14 in the reinforcing plate, the ends 15 of the lug may be made wider than the aperture 14, as shown in Fig. 1, thus providing shoulders 18 which engage with the plate 20 at each side of the aperture 14 and absolutely prevent the lug and plate from being separated by pulling the lug through the aperture.

The transversely extending sides of the 25 attaching lug are provided with aligned openings 19 through which the attaching key is inserted to secure the shoe to the brake head. These openings may be made of the required size and shape to receive the key and without running the cast metal into or around the projecting portion of the lug, or the attaching lug may be embedded in the cast metal as indicated at 20 in Fig. 3 to enlarge the dimensions of the 30 lug and provide a key opening of proper size. This cast iron is not provided for the purpose of strengthening or reinforcing the attaching lug for that is not necessary, the lug itself being sufficiently strong and 35 rigid for all purposes.

In Fig. 5 I have shown another form of reinforcing plate which is designated 22, the plate in this instance being made with straight edges neither beveled nor notched 40 around its periphery. The perforations 23 and 24 into which the cast metal of the shoe body flows in the casting operation are shown as transversely extending slots and circular openings, respectively, although it 45 will be obvious that the number, size, shape and arrangement of these perforations may be varied to suit the demands or meet the exigencies of any particular case. The construction of the attaching lug and the 50 shoe body may also be varied considerably without departing from the spirit or sacrificing any of the advantages of my invention.

My invention provides a permanent lock 60 between the plate and lug which is wholly unaffected by fractures in the shoe. The plate and lug will remain in locked engagement when the shoe body is worn down to the degree which necessitates its removal under the M. C. E. requirements, and

this engagement will continue even if the body is entirely lost from the plate. The body and plate are locked together as herein described, or in any other suitable manner, and with the plate and lug permanently 70 locked there is no chance for the shoe to fall away from the head in case of fracture. Thus my invention provides a shoe which may be retained in service until worn out, regardless of fractures, and it 75 thereby reduces the cost of maintenance but increases the efficiency of the shoe. The strap lug and plate are made of strong and substantial material which will not burn out in casting and the lug is sufficiently 80 strong to stand all the strains to which a brake shoe is subjected in service and in handling. The body metal may, as heretofore stated, be run up within and alongside the strap lug if desired to make the 85 lug conform to the requirements as to certain dimensions imposed by the Master Car Builders and some railway companies, but otherwise it is unnecessary.

What I claim and desire to secure by Letters Patent is:

1. A brake shoe comprising a reinforcing plate provided with an aperture, an attaching lug positioned in said aperture with its ends disposed beneath the transverse walls 95 of said aperture, and a body cast on said plate.

2. A brake shoe comprising a reinforcing plate provided with an aperture, an attaching lug positioned in said aperture and having its ends disposed beneath the transverse walls of said aperture and extending in opposite directions beneath the plate, and a body cast on said plate.

3. A brake shoe comprising a reinforcing 105 plate provided with an aperture, an attaching lug positioned in said aperture and having its ends engaged with the underside of said plate between said aperture and the ends of the plate, and a body cast on said 110 plate.

4. A brake shoe comprising a reinforcing plate provided with an aperture, an attaching lug formed of a bent metal strap positioned in said aperture and having its ends 115 extending lengthwise of the shoe beneath the plate, and a body cast on said plate.

5. A brake shoe comprising a reinforcing plate provided with a centrally disposed aperture, an attaching lug formed of a metal 120 strap positioned in said aperture, the ends of said lug extending longitudinally of the shoe beneath and adjacent to the underside of the plate, and a body cast on said plate.

6. A brake shoe comprising a reinforcing 125 plate provided with an aperture and a bent strap lug positioned in said aperture with upstanding portions thereof extending transversely of the shoe and provided with key openings, and a body cast on said plate. 130

7. A brake shoe comprising a reinforcing plate provided with an aperture and a strap lug positioned in said aperture with the protruding portions thereof extending transversely of the shoe and provided with openings and its ends extending lengthwise of the shoe beneath said plate, and a body cast on said plate.

8. A brake shoe comprising a reinforcing plate provided with an aperture, a strap lug positioned in said aperture and having end portions of greater width than said aperture anchored beneath the plate, and a body cast on said plate.

15 9. A brake shoe comprising a reinforcing plate provided with an aperture, a strap lug positioned in said aperture with its ends projecting longitudinally of the shoe, said ends being wider than the aperture to prevent withdrawal of the lug through the aperture, and a body cast on said plate.

20 10. A brake shoe comprising a reinforcing plate provided with an aperture, a strap lug positioned in said aperture with its ends extending lengthwise of the shoe beneath

the plate, said ends and the plate being provided with perforations to receive the body metal, and a body cast on said plate.

11. A brake shoe comprising a reinforcing plate provided with an aperture, a strap lug positioned in said aperture with its ends extending lengthwise of the shoe beneath the plate, said ends and the adjacent portions of the plate being provided with registering perforations to receive the body metal, and a body cast on said plate.

12. A brake shoe comprising a reinforcing plate provided with an aperture, a strap lug positioned in said aperture with its ends extending lengthwise of the shoe beneath the plate, said ends and the adjacent portions of the plate being provided with registering perforations to receive the body metal, the perforations in the plate being larger than those in the lug ends, and a body cast on said plate.
